UNITED STATES PATENT OFFICE.

THOMAS PARKER OTTERSON, OF KREBS, OKLAHOMA, ASSIGNOR OF ONE-HALF TO
PRESLEY ROBINS ALLEN, OF McALESTER, OKLAHOMA.

MINE-CAR WHEEL.

1,255,780.

Specification of Letters Patent. Patented Feb. 5, 1918.

Application filed August 8, 1917. Serial No. 185,075.

To all whom it may concern:

Be it known that I, THOMAS PARKER OTTERSON, a citizen of the United States, residing at Krebs, in the county of Pittsburg 5 and State of Oklahoma, have invented new and useful Improvements in Mine-Car Wheels, of which the following is a specification.

This invention relates to mine car wheels, and the objects of the same are to reduce the labor and cost of casting mine wheels; to remove all possibilities of wear on the central portion of the wheel adjacent to the axle and to impose all the wear upon and provide for 15 the replacement of interposed bearing devices between the wheel and axle; to render the rotation of the wheel easy by the installation of anti-frictional devices between the wheel proper and the axle, and also to 20 equip this type of wheel with a self-lubricating means which will have a lasting operation; to provide a mine wheel with inner and outer dust-proof structures or components that will also prevent back thrust of the 25 anti-frictional devices and protect the latter; and to provide for oiling or lubricating the wheel from the outside.

With these and other objects and advantages in view, the invention consists in 30 the construction and arrangement of the several parts which will be more fully hereinafter described and claimed.

In the drawing:—

Figure 1 is a perspective view of the improved mine car wheel and a portion of its axle.

Fig. 2 is a transverse vertical section through the wheel and axle.

Fig. 3 is a section through the wheel and axle taken in a plane at right angles to that shown by Fig. 2.

Fig. 4 is a detail perspective view of the wheel proper.

Fig. 5 is a view similar to Fig. 3 illustrating a slight modification or wherein anti-frictional devices are not used in the wheel bearing.

The numeral 5 designates a solid square axle with a shoulder 5^a at each extremity, 50 said axle being capable of standing a severe shock without bending and which can be readily constructed by an ordinary mechanic or blacksmith without requiring expensive lathe work. It is only necessary to shape 55 the improved axle by blacksmith methods

and at the same time preserve the necessary strength thereof, the axle being completed by boring the opposite ends, as at 6, to provide key pin pockets or seats. The wheel 7 is cast from suitable metal and 60 comprises an outer flanged rim 8 and an enlarged central bore 9 to loosely and rotatably fit over what may be termed a non-rotatable hub organization embodying separable and replaceable components in which 65 the said axle 5 is centrally disposed. The only wear on the wheel 7 occurs at the flanged rim 8 which engages the track rails, and this wear is reduced to a minimum. By thus constructing the wheel proper it can be 70 cheaply manufactured and will be strong and durable in its service.

The hub organization comprises essentially an outer steel bushing or sleeve 10, a box 11 with a central square bore 12 in which 75 the axle 5 is fitted, and an inner steel bushing or sleeve 13 fitted over the outer surface of the box 11, anti-frictional rollers or analogous devices 14 being introduced between the bushings or sleeves 10 and 13 and serving to provide an easy running wheel. The box 11 is formed with a circumferential oil chamber or groove 15 having a strip 16 of felt inserted therein and disposed throughout the interior of the chamber. An opening or feed port 17 is formed in the box 11 in communication with the chamber 15 and the latter is supplied with oil or lubricant from the outer side of the wheel through an oil hole 18. The bushing 13 also has an opening or port 19 therethrough registering with the opening or port 17 of the box 11 to permit the oil or lubricant to run into or be supplied to the space between the bushings 10 and 13 and to the anti-frictional 95 rollers 14. It will be seen that the wheel 7 is provided with an anti-frictional oiled or lubricated bearing having hard bushings to resist wear, and that all wear is relieved from the wheel proper and the box or hub center 11. Moreover, through the medium of the felt or other strip 16, the oil or lubricant is regularly and economically supplied to the wheel bearing by capillary action, and the chamber 15 may be charged from the outer side of the wheel with a quantity of oil or lubricant that will last for several months without replenishment, particularly in view of the economical dispensation of the oil from the chamber by means heretofore speci- 110

fied. It will also be noted that the oil chamber or reservoir is cast or formed separately with the box 11 from the wheel 7 and if damage to or breakage thereof occurs it 5 can be renewed independently of said wheel. The bushings 10 and 13 may be respectively withdrawn from the wheel bore 9 and the box 11 in the event of wear and replaced by similar devices and thereby maintain the 10 wheel in true running condition.

The improved wheel also includes an outside ring 20 to resist or take care of the thrust of the rollers 14, said ring having an offset 21 which projects into the wheel between 15 the bushings 10 and 13 and serves to keep dust out of the wheel bearing. The bushing 13 also has a rear or inner annular flange 22 with an opening 23 therein, and surrounding and fixed to the inner end 20 of the box 11 is a flange 24 having a dowel pin 25, the flange 22 removably bearing against the flange 24 with the pin 25 fitting in the opening 23. The flanges 22 and 24 close over the rear or inner portion of the 25 bore 9 of the wheel and form a dust guard at this point and also resist or take care of the back thrust of the rollers 14. The wheel and bearing components together with the ring 20 are held in removable operative 30 association on the axle extremity by a pin 26 inserted in the opening 5^a and through the axle extremity and bearing against the outer portions of the box 11 and ring 20.

The mine car wheel constructed as above 35 explained and embodying the features of the invention has many advantages relatively to mine car wheels now in use. In the improved wheel there is no possibility of the rollers 14 by wear embedding themselves in 40 the body of the wheel, and as said rollers are held between hard surfaces the wheel will be maintained in true and free running condition, and if the bushings or sleeves 10 and 13 become worn they may be easily replaced and the working life of the wheel 45 thereby prolonged at a small expense. By constructing or casting the oil box 11 separately from the wheel, the entire wheel is not crippled or rendered unfit for use in the 50 event that the said box break down as a result of excessive strain, sudden stoppage and wrecks, and, furthermore, the inconveniences and losses incidental to casting an oil box as an integral part of the wheel are 55 avoided. The improved wheel has inside means to withstand sudden thrusts when the wheel makes sudden turns or curves, provided by the flanges 22 and 24 next to the axle 5, and the outside ring 20 prevents 60 outer thrust. Usually, the wheels on mining cars in going around curves of tracks which are not graded to take care of the centripetal force of the cars are caused to wear unevenly either at the extreme inside or extreme 65 outside and thereby set up great fric-

tion and have to be discarded. The improved wheel herein disclosed overcomes these latter disadvantages through the resisting means provided to obviate this inner and outer wear. The parts or components of the hub or bearing for the improved wheel will be standardized and proportioned to various sizes of wheels so that they may be readily procured from a manufacturer or mine stock dealer and quickly 70 substituted for worn parts or components that have to be discarded with evident advantages in keeping mine cars in a practical running condition without requiring extensive delay in the use of the cars for the 75 purposes of repair.

In the construction shown by Fig. 4 the essential features of the improved wheel are preserved and the same reference characters are used, the anti-frictional rollers 14 being omitted. In this form of the wheel the two bushings or sleeves 10 and 13 are contiguous, or, one bears on the other. In this form of the wheel the same advantages are resident as in the preferred form first described, except that the wheel will not run quite as freely in view of the absence of the anti-frictional devices or rollers 14. 90

What is claimed is:—

1. A mine car wheel comprising a fixed 95 hub organization with a central box formed with a circumferential chamber having a textile lubricant absorbent therein and extending therearound and also having a bushing removably mounted thereon with an opening therethrough, a wheel having a bore with a bushing removably applied therein and rotatably mounted over the bushing of the box, and an axle angular in cross-section inserted and secured in the center of the box. 100

2. A mine car wheel comprising a fixed hub organization with a central box having an outer lubricant chamber therein, a bushing removably mounted thereon over the chamber, the chamber having a capillary feeding felt strip therein and the chamber and bushing having registering lubricant feeding openings therethrough, the felt strip extending around the lubricant chamber within the box, a wheel having a bore with a bushing removably applied therein and mounted over and rotatable on the box and its bushing, and a square axle inserted and secured in the center of the box. 110

3. A mine car wheel comprising a fixed 120 hub organization with a central box having an outer circumferential oil chamber with a bushing removably mounted thereover and provided with an opening registering with said chamber, a wheel having a bore with a bushing removably applied therein and rotatably mounted over the bushing of the box, anti-frictional devices between the two bushings, an outer removable ring disposed to have a portion thereof exposed between 125 130

- the bushings for engagement by the ends of the anti-frictional devices, and an axle angular in cross-section inserted and secured in the center of the box.
5. 4. A mine car wheel comprising a fixed hub organization with a central box having a bushing removably mounted thereon, a wheel having a bore with a bushing removably applied therein and rotatably mounted over the bushing of 25 the box, the box having lubricant carrying and supply means, and an outer dust guard and thrust ring to take up wear and disposed to engage the box and car wheel and having a portion thereof exposed between 30 the bushings and to engage the ends of the latter.
10. 5. A mine car wheel comprising an axle, a center box mounted on the axle and held over the bushing of the box, anti-frictional devices between the two bushings, a dust and thrust guard means at the inner side of the wheel, an outer dust guard and thrust ring, disposed to have a portion thereof exposed between the bushings for engagement by the ends of the anti-frictional devices, and an axle angular in cross-section inserted and secured in the center of the box.
15. 6. A mine car wheel comprising an axle, a center box mounted on the axle and held

against rotation, a bushing removably mounted on the said box, a wheel structure independent of and provided with a bore having a bushing removably applied therein and rotatably mounted over the bushing of 25 the box, the box having lubricant carrying and supply means, and an outer dust guard and thrust ring to take up wear and disposed to engage the box and car wheel and having a portion thereof exposed between 30 the bushings and to engage the ends of the latter.

In testimony whereof I have hereunto set my hand in presence of two subscribing witnesses.
